UNITED STATES PATENT OFFICE.

BENJAMIN WILLIAM ZIMMERLE, OF SUTTON, NEBRASKA.

PENHOLDER.

1,374,870.

Specification of Letters Patent. Patented Apr. 12, 1921.

Application filed May 19, 1920. Serial No. 382,616.

To all whom it may concern:

Be it known that I, BENJAMIN WILLIAM ZIMMERLE, a citizen of the United States, residing at Sutton, in the county of Clay 5 and State of Nebraska, have invented certain new and useful Improvements in Penholders, of which the following is a specification, reference being had therein to the accompanying drawing.

10 The invention relates to pen holders and has for its object to provide a pen holder comprising a staff on a reduced portion of which staff a sleeve is secured which sleeve is provided with external threads and a reduced portion, and to provide a sleeve to which cork or any other material is adhesively secured, which last mentioned sleeve is threaded on the first mentioned sleeve, and to provide means carried by the 15 sleeves for holding a pen point in such a manner that the pen point may be easily and quickly released when desired. Also to provide the outer sleeve with an annular flange for limiting the inward movement 20 of the pen point when the pen point is placed in the holder and to provide a second annular flange for engaging the pen point and holding the same against displacement.

25 With the above and other objects in view,

30 the invention resides in the combination and arrangement of parts as hereinafter set forth, shown in the drawings, described and claimed, it being understood that changes in the precise embodiment of the invention 35 may be made within the scope of what is claimed without departing from the spirit of the invention.

In the drawings:—

Figure 1 is a perspective view of the pen 40 holder showing a pen point therein.

Fig. 2 is a detail sectional view through the pen point holding end.

Fig. 3 is a view similar to Fig. 2 but showing a pen point in position.

45 Fig. 4 is a sectional view taken on line 4—4 of Fig. 2.

Referring to the drawing, the numeral 1 50 designates a pen staff and 2 a reduced portion thereof. Secured to the reduced portion 2 by means of a rivet 3 is a sleeve 4. The sleeve 4 is provided with a threaded portion 5 on which threaded portion 5, a pen point holding sleeve 6 is threaded. The sleeve 5 is provided with a reduced portion 7, which is axially disposed in the pen holding sleeve 6 and has its outer end split as at

8 so as to give when the pen point 9 is being clamped in the holder. The pen point holding sleeve 6 on its inner periphery at a point intermediate its length is provided with a stop flange 10 against which flange the rear end of the pen point 9 engages as at 11. Thus it will be seen that when the sleeve 6 is unscrewed and the pen point 9 placed in position that the flange 10 will limit the inward movement of the pen point so that the pen points will project beyond the end of the pen holder in a uniform distance. After the sleeve 6 has been unscrewed sufficiently to allow the insertion of the pen point 9, the sleeve 6 is screwed onto the threaded portion 5 of the sleeve 4, which will cause the annular flange 12 of the sleeve 6 to engage frictionally the outer face of the pen point 9 and hold the same against the 70 spring action of the member 13 formed by the split 8 in the sleeve 4. The outer sleeve 6 is provided with a finger engaging cork member 14, which may be adhesively joined thereto.

80 It will be seen that the flange 12 is limited as to the area of binding surface on the pen and that as the flange is moved outwardly around the split end of the sleeve 4 that the pen will be immediately released.

85 From the above it will be seen that a pen holder is provided which is positive in its operation and one wherein the releasing of the pen may be quickly accomplished. It will also be seen that during the initial 90 unscrewing action that the flange 10 will force the pen point 9 outwardly thereby breaking any adhesion of the pen point incident to corrosion.

95 The invention having been set forth what is claimed as new and useful is:—

1. The combination with a pen staff having a reduced portion, of a pen holder therefor comprising a sleeve carried by the reduced portion, said sleeve being provided 100 with an enlarged threaded portion and a reduced split portion, a second sleeve threaded on the enlarged threaded portion and having its inner periphery spaced from the outer periphery of the reduced portion 105 of the first mentioned sleeve, a pen point limiting flange on the inner periphery of the outer sleeve intermediate its length and a pen point holding and engaging flange on the inner periphery of the outer sleeve and 110 so positioned that it will surround the split end of the reduced portion of the inner

sleeve when the outer sleeve is screwed inwardly on the threaded portion of the inner sleeve.

2. A pen holder comprising inner and outer sleeves, said inner and outer sleeves being threaded together at their rear ends, the inner sleeve having its outer end reduced and split, and means carried on the inner

periphery of the outer sleeve for limiting the inward movement of a pen point and for 10 clamping said pen point against the split end of the inner sleeve.

In testimony whereof I hereunto affix my signature.

BENJAMIN WILLIAM ZIMMERLE.
